CABINET SEALING MEANS

William D. Rossiter, Sandusky, Ohio

Application May 12, 1943, Serial No. 486,645

13 Claims. (Cl. 70—465)

This invention relates to means for preventing the doors of cabinets and particularly those of fire extinguisher enclosures, or the like, from being opened by unauthorized persons without detection.

In the use of fire extinguishers, considerable difficulty has been encountered and damage done by reason of saboteurs and others rendering the extinguishers useless for the purpose intended by removing the chemicals contained therein and sometimes substituting an inflammable fluid such, for instance, as gasoline therefor, or otherwise preventing proper operation of the extinguisher.

The object of this invention is the provision of simple and efficient means for locking or sealing a cabinet in a manner to permit free and quick access to the interior thereof under emergency conditions and which will prevent unauthorized opening of the cabinet without ready detection of such opening.

The invention is fully described in the following specification, and one embodiment thereof illustrated in the accompanying drawing, in which—

Figure 1 is a perspective elevation of a cabinet for containing a fire extinguisher, with a part broken away and including the locking means of the invention; Fig. 2 is a cross-section on the line 2—2 in Fig. 1; Fig. 3 is an enlarged section on the line 3—3 in Fig. 2; Fig. 4 is a section similar to Fig. 2, with the sealing means broken and the door partly open, and Fig. 5 is an enlarged perspective view of a breakable plate constituting a part of the sealing means.

Referring to the drawing, 1 designates a container or cabinet, in the present instance, suitable for holding a fire extinguisher and having a hinged door 2 adapted to close a front opening. This door, in the present instance, is hinged for horizontal swinging movements and is intended to be engaged at its free edge portion and secured in closed position by a lock 3, the U-shaped shackle 4 of which is adapted to be engaged with an edge portion of the door through an opening 5 in the side or casing portion of the container within which the free edge of the door swings.

The portion of the door with which the shackle 4 has locking engagement comprises a breakable sealing plate 6, for instance of glass, which is mounted in an opening 7 of notch form in the free edge portion of the door. The wall of the opening 7 is provided therearound with a groove or recess 8 that has its ends opening at the free edge of the door, so that the plate 6 may be

removably inserted therein from such edge. When the plate is properly mounted in the opening 7, it substantially closes such opening, and has its free edge disposed substantially flush with the free edge of the door, and an aperture 9 is provided in the plate near such edge to receive the shackle 4 of the lock when one leg thereof has been passed through the casing opening 5. It is thus apparent that the lock shackle when engaged with the plate 6 and casing, as shown in Figs. 1 and 2, will prevent opening of the door unless the plate is broken to permit such opening.

For the purpose of breaking the seal plate 6 to permit quick access to the interior of the container 1, a striker member 12 is hinged at one end to the outer side of the door 2, as at 13, and has its free or swinging end disposed at the outer side of the door opening 7 and provided with one or more striker pins or lugs 14 at its inner side for engagement with the seal plate. It is preferable to provide two pins 14 disposed to have striking engagement with the plate 6 substantially in straddling relation to the shackle receiving aperture 9 therein, so that an inward striking movement of the member 12 against the plate will cause a breaking of the plate in a manner to release the sealing engagement of the lock shackle therewith and permit an opening of the door to render access to the contents of the cabinet. The outward swinging of the striker member 12 relative to the door is limited by a pin 15 at its inner end extending rearwardly beyond the hinge axis of the member in position to engage the door and stop the outward swinging of the member at a predetermined point.

A receptacle 16 is mounted on the rear side of the door 2 with at least a portion covering the inner side of the opening 7 so that broken pieces of the plate which fall inward from the plate, are received by and retained in this receptacle, as shown in Fig. 4. The end of the receptacle 16, at the free edge portion of the door, is inclined inwardly away from such edge and provided with a notch 17 through which the shackle of the lock may freely pass upon an opening or closing of the door. The receptacle 16 is preferably removable and for this reason is provided at its upper and lower free edges with ribs 18 for engaging within guide strips 19 attached to the inner side of the door, as best shown in Fig. 3.

It is apparent from the foregoing that the door 2 of the cabinet includes a breakable section 6 of glass or other suitable brittle material which is removable and replaceable in the opening 7 of the

door by simply sliding it into or out of such opening within the wall groove 8 thereof, and that the door when closed may be sealed against unauthorized opening by merely inserting the shackle of the lock 3 through the aperture 9 in the plate 6 and through the opening 5 in the door casing or side wall of the cabinet. When this has been done the door can either be quickly released for opening by breaking the plate 6, which is accomplished by striking such plate with the lugs 14 of the member 12, or by unlocking the lock 3 and removing its shackle from the engaged aperture. If, upon inspection, the plate 6 is found to be broken, there is a possibility that the contents of the cabinet have been tampered with, which may be definitely determined by examination. When the broken plate 6 has been replaced by a new plate, the cabinet may be again locked by engaging the shackle of the lock through the openings in the plate and cabinet wall.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. In a device of the class described, a door member having a breakable section forming an edge portion thereof with an opening therein with which a lock shackle may be engaged to retain the door in closed position, and striker means movably carried by the door and operable to strike the section to effect a breaking thereof.

2. In a device of the class described, a swingable door having an opening extending inwardly from the free edge portion thereof, a breakable plate removably mounted in said opening, being insertable therein inwardly from the open edge of the door and having an aperture for receiving a lock shackle to normally retain the door in closed position, and a striker member movably carried by the door and having a part movable into engagement with the plate to effect a breaking thereof to release the shackle.

3. In combination, a cabinet forming a door casing, a door hingedly mounted in said casing and having a fragile breakable section removably and replaceably mounted in the door in exposed relation to its swinging edge, said section and casing having adjacent shackle receiving openings therein, and a lock having a U-shaped shackle for locking engagement through said openings.

4. In combination, a cabinet forming a door casing, a door hingedly mounted in said casing and having a breakable section removably and replaceably mounted in the door in exposed relation to its swinging edge, said section and casing having adjacent lock shackle receiving openings therein, a lock having a shackle for locking engagement through said openings, and a striker member hinged to the outer side of said door and operable when swung inward to have striking and breaking engagement with said plate to release the engagement of the lock shackle therewith and permitting an opening of the door.

5. In combination, a cabinet forming a door casing, a door hingedly mounted in said casing and having an opening therein extending inwardly toward its hinge edge from its swinging edge, a breakable plate mounted in said opening and removable therefrom and replaceable therein through the free edge portion of the door when the door is in open position, said plate and casing

having adjacent openings for receiving a lock shackle, a lock having a shackle releasably engageable with said plate and casing through the openings therein to retain the door in closed position, and means mounted on the door and adapted to have striking engagement with the plate to effect a breaking thereof and a release of its engagement with the lock shackle.

6. The combination with a cabinet forming a door casing, and a door hingedly mounted in said casing and having an opening at its swinging edge portion, a breakable plate mounted in said opening and replaceable therein through the free edge portion of the door when in open position, said plate and casing having adjacent openings for receiving a lock shackle to retain the door in closed position, and a receptacle carried by the inner side of the door adjacent to said opening for receiving fragments of the plate when broken.

7. The combination with a cabinet forming a door casing and a door hingedly mounted in said casing and having an opening at its swinging edge portion, a breakable plate mounted in said opening and replaceable therein through the free edge portion of the door when in open position, said plate and casing having adjacent openings for receiving a lock shackle to retain the door in closed position, a receptacle removably carried by the door at its inner side in covering relation to said opening for catching fragments of the plate when broken.

8. A combination as called for in claim 6, together with striker means hingedly carried by the door at its outer side and operable to strike and break said plate.

9. The combination with a cabinet forming a door casing and a door hingedly mounted in said casing and having an opening at its swinging edge portion, a breakable plate mounted in said opening and replaceable therein through the free edge portion of the door when in open position, said plate and casing having adjacent openings for receiving a lock shackle to retain the door in closed position, and a striker member hingedly carried by the door at its outer side and operable to strike and break said plate, the plate contacting portion of said member comprising spaced lugs engageable with said plate adjacent to and above and below its shackle receiving opening.

10. A combination as called for in claim 7, together with striker means hingedly carried by the door at its outer side and operable to strike and break said plate.

11. The combination with a cabinet having an opening to its interior and a movable closure for said opening, of a lock attached to one of said cabinet and closure and a cooperating locking part attached to the other whereby when said lock and part are engaged the closure is retained in closed position, one of said part and the cooperating portion of the lock being of fragile breakable material whereby it will be broken by a blow thereagainst and permit an opening of the closure.

12. The combination with a cabinet having an opening to its interior and a movable closure for said opening, of a replaceable plate of fragile breakable material attached to an edge portion of one of said cabinet and closure, and a lock attached to the other of said cabinet and closure and operable to have locking engagement with the plate to retain the closure in closed position, said plate being broken by a blow exerted from

without the cabinet to effect a release of the locking engagement of the lock and closure.

13. The combination with a cabinet having an opening to its interior and a movable closure for said opening, of a replaceable plate of fragile breakable material attached to an edge portion of one of said cabinet and closure, and a lock

5 attached to the other of said cabinet and closure and operable to have locking engagement with the plate to retain the closure in closed position, and a striker means movably carried by one of said cabinet and closure and operable to strike the plate to effect a breaking thereof.

WILLIAM D. ROSSITER.
